INFLATABLE ARTICLE FORM

John J. Lee, Sandusky, Ohio, assignor to The Barr Rubber Products Company, Sandusky, Ohio, a corporation of Ohio

Application July 25, 1934, Serial No. 736,921

8 Claims. (Cl. 18—41)

This invention relates to a new and improved form for use in the production of inflatable articles, such as toys, for example, and has for certain of its objects the provision of a form which is simple, enables the production of articles superior to those produced by present day forms and methods, and is relatively inexpensive in comparison with the results obtained in the use thereof.

10 This application is a continuation in part of my copending application Serial No. 698,646, filed November 18, 1933.

An object of the invention is to provide a flexible or collapsible mold or form simulating an article to be produced whereby it will be possible to produce inflatable articles of a type which has heretofore been practically impossible to produce.

Another object of the invention is to provide a form or mold by means of which it will be possible 20 to produce inflatable articles which are seamless.

A further object is to provide a form or mold upon which inflatable articles may be produced by a dipping process employing liquid latex, rubber, balata, resins or similar substances, as distinguished from the present methods of die cutting calendered rubber.

Another object is to provide a form or mold upon which may be produced inflatable articles simulating animals in which the legs are separate and distinct so that the article when inflated is capable of standing in its natural position without any other means of support.

The invention may be briefly summarized as consisting in the provision of a new form or mold upon which inflatable articles may be produced, as hereinafter described and claimed.

Referring to the drawings:

Fig. 1 is a perspective view of an inflated article simulating a dog and made upon a mold or form embodying the invention.

Fig. 2 is a side elevation of the inflatable article shown in Fig. 1 and shows the mold or form employed and its relationship with respect to said article.

Fig. 3 is a transverse sectional view taken on line 3—3 of Fig. 2 and particularly illustrates the arrangement of the legs of the article and the manner in which the mold is arranged therein.

50 Fig. 4 is a perspective view of a form or mold embodying the invention, said form or mold simulating a different animal from that shown in Figs. 1 and 2, namely, a giraffe.

Fig. 5 is a side elevation of a different inflatable article from that shown in the previous views, the

form or mold being illustrated as arranged within the article.

Fig. 6 is a front elevation of an inflatable article simulating a cat and shows the article after the mold or form has been removed therefrom.

Fig. 7 illustrates the mold or form used in the production of the articles shown in Fig. 6.

Fig. 8 illustrates a flexible or collapsible mold or form embodying the invention and made of a rubber material.

Fig. 9 is a fragmentary cross-sectional view of a mold or form embodying the present invention and having embossed or raised portions thereon.

Fig. 10 is a fragmentary cross-sectional view of a mold or form embodying the invention and provided with a depressed portion.

In the drawings Fig. 1 is illustrative of an inflated article 20 simulating a dog and produced on a form or mold embodying the invention as will be hereinafter described. To begin the explanation it will probably be well to explain that the form and method employed produce articles adapted for inflation without distortion or substantial distortion. In other words, an inflatable article is one which is adapted to be inflated to its normal limit without subjecting the rubber to overexpansion as distinguished from the ordinary type of rubber balloon or similar article which is subject to distortion upon inflation.

The dog 20 has a plurality of legs 21 formed integral with the body portion and also made hollow so as to be inflatable. When the dog is inflated it is adapted to be supported by the legs 21 in an upright position to resemble a natural animal as much as possible. Ears 22, made of rubber, are secured at 23 to the head portion of the dog by means of a suitable adhesive or any other suitable means in such a manner as to permit the ears to move. At the rear portion of the dog there is provided a tail 24 of hollow construction so that when the same is inflated it will remain in a predetermined position and in the end of the tail 24 an inflating device 25 of the usual type is secured.

In Fig. 2 a form 26 is shown simulating the dog 20, shown in Fig. 1 and from which it will be readily apparent that the size of the form 26 is substantially the same as the size of the inflated dog 20. The form 26 comprises a body member 27, an integral tail portion 28 and depending leg portions 29, there being a pair of front legs and a pair of hind legs extending laterally as shown in Fig. 3. The upper portions of these legs are provided with substantially circular extensions 30 which are secured to the body portion 27 by 55

an adhesive or other suitable means. The legs 29 are maintained in separated position, as shown in Fig. 3, by means of inverted V-shaped spacers 31 which extend longitudinally between the legs 29 and the adjacent portion of the body 27, the spacers being secured thereto by an adhesive or any other suitable means. At the rear portion of the body 27 is an extension 32 which serves as a means by which the form 26 may be submerged. 10 Around the edges of the circular portions 30 a filler is employed so as to provide a tapering surface between the outer surfaces of the portions 30 and the adjacent outer surfaces of the body 27 so that form marks or blemishes will not appear on 15 the ultimate article.

The form 26 may be made of any suitable flexible or collapsible material, as for example, a filled manila paper of sufficient rigidity to be submerged in a rubber solution and is of a non-re- 20 usable and collapsible type for reasons which will be later described. While this type of form may be used for carrying out the purpose of the method, other types of forms may be employed wherein the same result is obtained.

25 In practicing the method the form 26 is submerged in a liquid rubber solution such as liquid latex, although dispersions of rubber, balata, resins or similar substances may be substituted, by holding the extension 32 and submerging the form 30 so as to apply a rubber coating upon the form as indicated by 33. This liquid rubber solution may be of any desired color. The form 26 is maintained in the rubber solution for the required 35 length of time, depending upon the thickness of rubber which is desired and is then withdrawn and permitted to dry at room temperature for a period of approximately thirty minutes. Preferably, the form with the rubber coating thereon is then cured by placing the same in an oven for 40 a further period of approximately thirty minutes at a temperature of approximately 180° F., although other methods may be employed. After the rubber coating upon the form is cured, the form 26 is removed from the rubber article by 45 withdrawing the form through the opening 34 provided in the article by the extension 32. The removal of the form 26 is made possible and easily accomplished due to the flexibility or destructibility of the form, inasmuch as the form 50 may be crumbled inside of the rubber article and thus materially reduced in size so that it may be easily withdrawn through the opening 34. The rubber extension 35 surrounding the form extension 32 at one end of the dog adjacent the tail 55 24 is then trimmed off by any desired tool and the adjacent edges are secured together by an adhesive to provide an air-tight seal 36, as shown in Fig. 1. It will be noted that the article or dog, as in this case, is otherwise seamless which adds 60 life and strength to the article as there are no seams which are subject to wear and resultant breakage. The end of the tail 24 is provided with an opening and the inflating device 25, already referred to, is secured therein so that the article 65 or dog may be inflated. When the article or dog 20 is inflated, the legs 21, being hollow, are likewise inflated and, due to the construction of the form heretofore explained, remain in an extended and separated position relatively so that the 70 dog may stand otherwise unsupported upon its legs.

To facilitate the stripping operation of the rubber article from the form 26, the latter may be treated in a solution known as a coagulant or similar material known in the art, which prevents any

tendency of the liquid rubber solution adhering to the surface of the form, the preferred method being to have a dusting material suspended in the coagulant to assist the stripping of the rubber film from the flexible form. The addition of this material eliminates the possibility of the rubber 5 sticking to the form during curing.

In Fig. 4 a form 37, simulating a giraffe, is illustrated, showing the many types of characters or animals which may be produced in accordance 10 with the present method. Attention is directed to the fact that the extension, such as 38, by which the form is supported while being submerged in the liquid rubber solution, should be located at a point remote from the extensions of the animal, 15 such as the legs and tail, etc., so that after the form has been dipped and cured and it is desired to strip the rubber article from the the form, these extensions, produced upon the form, will be more readily removable. Furthermore, it is to be 20 noted that it is preferable to provide the rubber articles with an inflating device which is located in an extension remote from the sealed portion through which the form is removed.

In Figs. 5 to 10, inclusive, various types of inflatable articles and toys are illustrated which are of a substantially flat nature, that is, types of articles which are not intended to stand unassisted. In Fig. 5 a flying horse is shown, the form being indicated by the numeral 39 and the rubber coating indicated by the numeral 40. In this particular instance the form 39 has a central opening 41 which provides in the resultant article a similar opening. It will be readily appreciated that such an article as this could not possibly be produced according to the methods at present available, that is, in the die cut method in which sheets of calendered rubber are employed and the adjacent edges of the sheets along the contour of the article secured together by a suitable adhesive which results in a substantially continuous seam. In this type, however, according to the present method the rubber article 40 is readily stripped from the form 39 by breaking the form along the dotted line at the location indicated by the numeral 42, that is, along a portion between the opening 41 and the outer edge of the form. This permits the form 39 to be removed through the opening 43 provided in the forward end of the article by the extension 44 which is 50 formed integral with the forward end of the form.

In Figs. 6 and 7 is illustrated an article different from those previously explained and the form upon which the article is made. In Fig. 7 a form 57 is shown which simulates a cat and this form 55 has the extension 58 provided at the upper portion thereof by which the form may be supported while being submerged in the liquid rubber solution. Fig. 6 illustrates the rubber article after it has been stripped from the form 57. In this case 60 in the dipping operation the form 57 is submerged in a liquid rubber solution of any desired color, for example yellow, up to the point 59, indicated in Fig. 6, to apply a coating thereon. This coating is permitted to dry and the form with the yellow 65 rubber coating is then submerged in a liquid rubber solution of a different color, for example blue, up to point 60. The form with the blue rubber coating is then removed from the solution and permitted to dry. It is next cured in the manner already stated and after the curing operation, but prior to stripping from the mold 57, the face 61 is printed upon the head portion and the surface ornamentation indicated at 62 applied to the body portion of the rubber article. After this 70

printing operation, the rubber article is stripped from the form 57 and is in the condition shown in Fig. 6. It should be understood that any number of colors may be applied to the rubber article 5 by submerging the form in any number of colored liquid rubber solutions. The application of each rubber solution, however, results in the rubber article having that much more thickness.

As previously stated, the present invention 10 contains a flexible or collapsible form which may be dipped into the latex or other material and from which the article may be easily removed. These forms may be made of any suitable material having the desired flexibility as, for example, 15 the paper form previously described which possesses certain advantages in its use and is intended to be destroyed during its removal from the article. It has been found, however, that when large quantities of the inflatable articles are being manufactured the expense in making the forms of destructible paper or other destructible material is quite a factor in the actual cost of manufacture. I have, therefore, constructed a 20 collapsible or flexible form made of rubber, rigid enough to be dipped into the latex or other material, but easily removed from the article after the latter has been cured.

Preferably, the rubber forms are made of a 25 tough rubber which will not break when flexed as, for example, a rubber made by mixing rubber and suitable compounds in a manner well known in the rubber industry. The rubber forms may be made in a mold and may have any desired shape 30 or thickness, or they may be blanked out from sheet rubber. It will always be possible to use 35 a rubber form except for those articles which are provided within their outline or periphery with an opening, since it is necessary in connection with articles of this kind to break the form on opposite sides of the opening in order to remove 40 it from the article. An article of the type just referred to is illustrated in Fig. 5, wherein, because of the opening 41 it is necessary to break the form along the line 42, as previously described.

45 Rubber forms may be employed for making the article shown in Figs. 1, 2, 4, 6, and 7, as well as the form shown in Fig. 8. This latter form simulates a crab and comprises a body portion 63, side extension 64 integral therewith and rearwardly 50 extending fingers 65. Formed integral with the body 63 is an extension 66 which may be held in any suitable device, while the form is being dipped in the latex or other solution. Of course, a rubber form of this character may be used over and over 55 again with the result that an enormous saving in cost is effected.

In Fig. 9 a form is shown as provided with raised 60 portions 75 which serve to provide rough surfaces on the article, which surfaces later may be printed in a manner such that the raised portions take the ink and the portions in between do not take the ink thus making it possible to simulate hair on the article.

A form, such as shown in Fig. 9, may be made 65 either of paper or of rubber. If the form is a paper form the raised portions 75 are embossed on the paper. As is well known, embossed paper is only embossed on one side, consequently, if the form were constructed of a single sheet of paper 70 the roughened surface would only be on one side with the result that the articles would only have a roughened surface on one side. If the form is for an animal it is necessary to have the roughened effect on both sides, in which event 75 the form would be constructed of two embossed

sheets of paper having their smooth sides pasted together and leaving the roughened surfaces on the outside of the form. If the form shown in Fig. 9 is made of rubber, it would be produced in a mold and would have the desired thickness 5 with the roughened surfaces upon one or both sides, as desired.

In Fig. 10 there is illustrated a form having a 10 depressed portion 77 so that when the form is dipped in the coagulant it will take up unequal amounts of the material and thus produce an unevenness of gauge and of surface in the finished rubber film causing uneven distention of the article when inflated. The form shown in Fig. 10 may be formed either of paper or of rubber, 15 or other suitable flexible or collapsible material, as the case may be.

As in the case of the paper forms, the rubber forms are treated in a solution to prevent the 20 articles sticking to the forms and to facilitate their removal therefrom, the preferred method being to have a dusting material suspended in the coagulant.

It will also be noted that it will be possible 25 after dipping any of the forms herein described in the coagulant and drying, to then superimpose on the dried coagulant by brushing, stamping or printing a film of the same or a stronger coagulant thus securing rubber films of non-uniform gauge 30 or thickness for the purpose of providing reinforced portions which, when the article is inflated, will not distend in the same manner as the rest of the article.

It is also possible to secure to either the paper 35 or rubber forms, such appendages as ears, horns, tails of birds, etc. In the case of paper forms the forms may be moistened and the appendages positioned thereon after which the forms and appendages are dried in a heated mold. In the case of the rubber form the appendages may be 40 vulcanized or cemented to the form, as is well understood.

While I have described the preferred embodiments of the invention, it is to be understood that I am not to be limited thereto inasmuch as 45 changes and modifications may be resorted to without departing from the spirit of the invention as defined in the appended claims.

Having thus described my invention, what I 50 claim is:

1. A form for use in producing by the dipping process inflatable seamless articles comprising a substantially flat, thin, flexible body portion provided with flexible extensions which project from the body portion laterally of the central plane 55 thereof and are adapted to form appendages on the article located laterally of the central plane of the article when inflated.

2. A collapsible form for use in producing by the dipping process inflatable seamless articles comprising a thin, substantially flat, flexible body having an extension in the plane of the body by which it may be supported during the dipping operation and having also flexible extensions 60 which project from the body portion laterally of the central plane thereof and are adapted to form appendages located laterally of the central plane of the body when the article is inflated.

3. A collapsible form for use in producing by the dipping process inflatable seamless articles comprising a thin, flexible, substantially flat body portion with an extension in the plane of the body portion by which the form may be supported during the dipping operation and provided also 70 with flexible extensions projecting from the plane 75

of the body and adapted to form lateral appendages on the article.

4. A collapsible form for use in producing by the dipping process inflatable seamless articles comprising a thin, substantially flat, flexible body portion provided with flexible divergent extensions projecting laterally from the plane of the body and adapted to form lateral appendages on the article produced on the form.

5. A collapsible form for use in producing by the dipping process inflatable seamless articles comprising a thin, substantially flat, flexible body portion having one or more extensions in the plane of the body including an extension by which the form may be supported during the dipping operation and having also extensions in divergent relation projecting laterally from the plane of the body and adapted to form lateral appendages on the article.

10 6. A collapsible form for use in producing by the dipping process inflatable seamless articles comprising a thin, substantially flat, flexible body portion having flexible extensions secured to the

sides thereof and projecting laterally from the body portion so as to form lateral appendages on the article.

15 7. A collapsible form for use in producing by the dipping process inflatable seamless articles comprising a thin, substantially flat, flexible body portion with an extension in the plane of the body portion by which the form may be supported during the dipping operation and provided also with flexible extensions which are secured to the sides of the body portion and adapted to form lateral appendages on the article, said form being produced from readily severable material.

8. A form for use in producing by the dipping process, inflatable seamless articles comprising a substantially flat, thin, flexible body portion provided with flexible extensions which project from the body portion laterally of the central plane thereof and are adapted to form appendages on the article located laterally of the central plane of the article when inflated, and means for holding said flexible extensions in spaced relation.

JOHN J. LEE.
